TRIMMING MACHINE

Fred Ashworth, Wenham, Mass., assignor to
 United Shoe Machinery Corporation, Borough
 of Flemington, N. J., a corporation of New
 Jersey

Application April 18, 1940, Serial No. 338,357

22 Claims.

(Cl. 12—1)

This invention relates to methods of and machines for trimming shoe parts and is illustrated as embodied in a machine for trimming the upper margins of moccasin vamps.

In one method of making moccasins as disclosed in application Serial No. 240,546, filed November 15, 1938, in the names of Ashworth and Baker, the vamp is stretched over a last and held thereto by a clamp which surrounds the forepart of the vamp. After the attachment of the clamp to the last, the upper margin of the vamp is trimmed with a bevel cut to prepare the vamp for the attachment of a toe piece which closes the opening in the forepart of the vamp. This trimming operation is performed manually by the operator, the upper margin of the clamp forming a guide for a hand knife. In order to secure an even cut with the proper bevel, this trimming operation is slow and requires a great amount of skill on the part of the operator. When the moccasin is lasted, bunches or wrinkles are usually formed at the toe portion of the vamp. The presence of these bunches increases the difficulty of trimming at the toe portion and only with the exercise of considerable care and skill is it possible to trim this portion of the vamp evenly.

One object of this invention is the provision of an improved method of and machine for trimming the vamp of a moccasin which eliminates the difficulties heretofore encountered in securing an even trim, and reduces the skill and effort required by the operator, as well as the time required to complete a trimming operation.

As a feature of the invention, tension is applied to the trimmed surplus portion of the margin during the trimming operation, particularly while traversing the toe portion of the vamp, the application of this tension tending to smooth out the bunches or wrinkles at the margin of the vamp so that trimming of the toe portion of the vamp is no more difficult than the trimming of the sides which may be substantially devoid of bunches.

In the illustrated embodiment of my invention, the work is fed by a pair of feed rolls which engage opposite sides of the portion of the margin to be removed, there being a guide associated with one of the feed rolls which is arranged to hook over the top margin of the clamp to guide the work relative thereto. A reciprocable knife adjacent to the guide and operating in shearing relation to one of the feed rolls is arranged to trim the margin of the vamp along a line adjacent to and parallel to the upper margin of

the clamp. The guide is so disposed relative to the feed rolls that it holds the margin of the vamp at the proper angle relative to the knife during the trimming operation so that the stock will be cut with the proper bevel. Additional rolls arranged to engage opposite sides of the trimmed surplus portion of the margin are rotated sufficiently fast to exert tension thereon to stretch out the bunches in the margin of the vamp around the toe portion as it is trimmed, thus eliminating the difficulties normally encountered in trimming this portion of the moccasin vamp. These tensioning rolls are shaped to exert an upward pull on the surplus portion further to increase the stretching action on the bunches at the margin where the trimming takes place.

These and other features of the invention will now be described in the following specification, reference being had to the accompanying drawings, in which

Fig. 1 is a side elevation of the head of a machine in which the invention is embodied;

Fig. 2 is a plan view of the machine, portions thereof being broken away; and

Fig. 3 is an enlarged detail view of the working parts of the machine, illustrating a piece of work being trimmed thereby.

The machine is shown to comprise a base 10 to 30 the upper end of which at one side thereof is secured by screws 14 a feed roll supporting member 12. The rearward portion of the member 12 has a bearing portion 16 (Fig. 2) in which is journaled one end of a drive shaft 18. The opposite end of the drive shaft 18 is journaled in a bearing 20 formed at the lower rearward end of a frame member 22 secured to the opposite side of the base 10 and extending above the member 12. A pulley 24 is secured to the drive shaft 18 and is connected by a belt 26 to a suitable driving means.

In the forward end of the roll support 12 is journaled a vertically extending shaft 30 (Fig. 1) to the upper end of which is secured a frusto-conical feed roll 32. The lower end of the shaft 30 carries a bevel gear 34 which engages a bevel gear 36 carried by the forward end of a shaft 38 journaled in bearings 40 and 42 in the lower side of the feed roll supporting member 12, the rearward end of the shaft 38 carrying a worm gear 44 which engages with worm teeth 46 (Fig. 2) cut in the periphery of the drive shaft 18.

A second frusto-conical feed roll 48 is carried by the lower end of a shaft 50 journaled in a bearing sleeve 52. This bearing sleeve is in turn

pivoted by means of a laterally and rearwardly extending arm 54, on a shaft 56 extending transversely across the upper forward portion of the machine and journaled in bearings 58 and 60 formed at the upper end of the frame member 22. The upper end of the shaft 50 carries a worm gear 62 which engages with worm teeth 64 (Fig. 2) cut in the periphery of the shaft 56. The shaft 56 carries a pulley 68 connected by a belt 70 with a pulley 72 on the drive shaft 18. The feed rolls 32 and 48 are thus rotated in timed relation and are arranged to rotate at the same peripheral speeds. The pivotal mounting of the bearing sleeve 52 in which the shaft 50 is journaled on the shaft 56 permits rotative movement of the bearing without disengaging the gears 62 and 64, to permit the feed roll 48 to be moved away from the feed roll 32. The rearward end of the arm 54 connected to the bearing member 52 is connected by a treadle rod 76 to a treadle (not shown). A spring 78 surrounds the treadle rod 76 and acts between a collar 80 mounted thereon and a plate 82 secured to the base 10 to urge the treadle rod 76 upwardly which in turn urges the feed roll 48 toward the feed roll 32. Upward movement of the treadle rod 76 and consequently movement of the feed roll 48 toward the feed roll 32, is limited by a collar 84 secured to the treadle rod and arranged to engage the under side of the plate 82. The feed roll 48 is thus normally maintained in feeding relation with the feed roll 32 but may be moved away therefrom by depressing the treadle in order to facilitate presentation of the work to the machine or to interrupt the feeding movement whenever desired.

In order to guide the work relative to the feed rolls, a guide 86 is mounted below the feed roll 32. This guide is formed at the upper end of a member 88 secured by screws 90 to the forward end of the roll supporting member 12. The guide 86 as indicated in Fig. 3 is arranged to hook over the upper margin of a clamp C by which the vamp V of a moccasin is secured to a last L. The forward face of the guide 86 forms a continuation of the feed roll 32 to prevent bending of the margin of the vamp below the feed roll 32, thus to insure trimming of the margin at the desired angle. The upper margin of the clamp is maintained against the underside of the guide 86 so that the vamp may be trimmed along a line parallel to the upper margin of the clamp.

The work is trimmed by a knife 92 held by a plate 94 to the upper surface of a slide 96. The plate 94 by which the knife is secured to the slide is slotted in its under surface to receive the knife and maintain it in the proper angular relationship relative to the slide. In order to permit the knife to be adjusted laterally relative to the guide 86, the plate 94 is secured to the slide by a screw 98 threaded into the slide and passing through an elongated opening in the plate. The slide 96 is reciprocated so that the knife 92 may sever the work with a draw cut, the lower surface of the feed roll 32 forming a shearing surface across which the cutting edge of the knife moves.

The slide 96 is supported in a slideway formed by the adjacent surfaces of the roll supporting member 12, the frame member 22, and the base 10. The rearward end of the slide 96 is pivotally connected to a strap 100 surrounding an eccentric 102 mounted on the drive shaft 18 between the bearings 16 and 20. Thus as the shaft 18 is rotated the knife 92 will be reciprocated in

timed relation with the feed rolls 32 and 48 to sever the surplus stock from the margin of the moccasin vamp as it is fed thereby.

The mechanism thus far described will effectively trim the surplus stock along the top margin of the vamp at the sides thereof where the material is substantially free of bunches. In trimming around the toe portion, however, it is desirable to apply a tension to the surplus 5 trimmed portion of the vamp to smooth out the leather at the point of trimming. Accordingly, a pair of rolls 110 and 112 are arranged beyond the knife 92 in the direction of feed to grip opposite sides of the surplus material as shown in 10 Fig. 3. The work contacting portions of these rolls are driven at a somewhat higher peripheral 15 speed than that of the feed rolls 32 and 48 to exert a pull on the material where the trimming is taking place. These rolls are grooved as indicated in Fig. 3 to exert a substantial gripping 20 action upon the material and are conical in shape with the small ends of the rolls adjacent to the feed rolls 32 and 48. By reason of this 25 shape of the rolls 110 and 112, the surplus material engaged thereby tends to ride upwardly between the rolls, thus increasing the pull exerted on the material adjacent to the knife and further facilitating the trimming of the vamp.

The roll 110 is mounted on an upwardly and 30 rearwardly inclined shaft 114 journaled in a bearing sleeve 116. The upper end of the shaft 114 carries a worm gear 118 driven from a worm 35 120 mounted on a shaft 122 journaled in the upper part of the machine. The shaft 122 has secured thereto a pulley 124 connected by a belt 126 with a pulley 128 fast on the drive shaft 18.

The feed roll 112 is arranged to be moved toward and away from the roll 110. The feed roll 112 is mounted at the lower end of a shaft 130 40 extending upwardly and rearwardly of the machine, this shaft being journaled in a bearing sleeve 132 having an arm 134 (Fig. 2) terminating in a bearing 135 which surrounds the shaft 122. A worm gear 136 carried by the upper 45 end of the shaft 130 is also driven from the worm 120 so that the feed rolls 110 and 112 rotate constantly at the same speeds. Since the bearing sleeve 132 is pivotally mounted on the shaft 122, the roll 112 may be moved away from the roll 110 without interfering with the drive from the shaft 122 to the shaft 130 on which the roll 112 is carried.

The feed roll 112 is normally maintained out 50 of driving engagement with the roll 110 and is arranged to be moved toward the roll 110 by the operator when desired. A treadle rod 140 (Fig. 1) is connected at 142 to the bearing sleeve 132 and is urged upwardly by a spring 144 acting between the base 10 of the machine and a collar 146 secured to the treadle rod 140. By stepping 55 on a treadle (not shown) the treadle rod 140 may be moved downwardly to move the roll 112 down into position indicated in Fig. 3 to grip the surplus material trimmed from the margin of the vamp and to exert a pull on the material being trimmed at the point where the trimming is taking place. The surplus stock will tend to ride upwardly between the rolls 110 and 112 by reason of the 60 conical shapes of the rolls so as to increase the effectiveness of the tension applied to the surplus material.

As indicated in Fig. 3 the knife 92 trims the 65 vamp with a beveled cut along a line parallel to and slightly above the upper edge of the clamp C. After the material has thus been trimmed, ce-

ment is applied to the trimmed edge of the vamp and the toe piece which is to form the top of the forepart of the moccasin is secured thereto by the cement. Since the vamp, after it has been trimmed, extends slightly above the top margin of the clamp, there is less danger of any cement being applied to the clamp when the cement is applied to the trimmed edge of the vamp than if the vamp were to be trimmed flush with the top edge of the clamp.

By the use of this apparatus it is possible to trim rapidly the vamp of a moccasin with a clean even cut, beveled at an angle which is readily maintained uniform, to facilitate the subsequent attachment of a toe piece thereto. The tensioning rolls 110 and 112 may be used or not as desired and ordinarily will be used when trimming portions which have been bunched during the lasting operation, as around the toe portions. It may be desirable however to use these rolls at all times even when trimming along the sides of a vamp.

Having thus described my invention, what I claim as new and desire to secure by Letters Patent of the United States is:

1. In a machine for trimming the vamp of a moccasin secured to a last by a clamp surrounding the vamp, a gage against which the upper margin of the clamp may be held to guide the work, said gage including a portion arranged to project between the clamp and the vamp, said portion having a surface arranged to support the vamp for the trimming operation, and means adjacent to said gage arranged to trim the vamp along a line parallel to and adjacent to the top margin of the clamp.

2. In a machine for trimming the vamp of a moccasin secured to a last by a clamp surrounding the vamp, a gage against which the upper margin of the clamp may be held to guide the work, said gage including a portion arranged to project between the clamp and the vamp, said portion having a surface arranged to support the vamp for the trimming operation, and means for trimming the vamp at an acute angle with respect to the sides of the vamp, said trimming means being mounted adjacent to said gage and arranged to trim the vamp along the line parallel to and adjacent to the top margin of the clamp.

3. In a machine for trimming the vamp of a moccasin secured to a last by a clamp surrounding the vamp, a gage against which the upper margin of the clamp may be held to guide the work, said gage including a portion arranged to project between the clamp and the vamp, means adjacent to said gage arranged to trim the vamp along a line parallel to and adjacent to the top margin of the clamp, and means engaging the untrimmed marginal portion of the vamp for feeding the vamp by the trimming means.

4. In a machine for trimming the vamp of a moccasin secured to a last by a clamp surrounding the vamp, a gage against which the upper margin of the clamp may be held to guide the work, said gage including a portion arranged to project between the clamp and the vamp, means adjacent to said gage arranged to trim the vamp along a line parallel to and adjacent to the top margin of the clamp, means engaging the untrimmed portion of the vamp for feeding the vamp by the trimming means, and means for applying tension to the surplus stock after it has been trimmed.

5. In a machine for trimming the vamp of a moccasin secured to a last by a clamp surround-

ing the vamp, a gage against which the upper margin of the clamp may be held to guide the work, said gage including a portion arranged to project between the clamp and the vamp, a pair of feed rolls arranged to engage opposite sides of the untrimmed portion of the vamp projecting beyond the clamp, said feed rolls being located adjacent to said gage, means positioned adjacent to said gage for trimming the vamp along a line parallel to and adjacent to the top margin of the clamp, and a pair of driven rolls arranged to engage opposite sides of the trimmed surplus portion of the vamp for applying tension thereto.

6. In a machine for trimming the vamp of a moccasin secured to a last by a clamp surrounding the vamp, a gage against which the upper margin of the clamp may be held to guide the work, said gage including a portion arranged to project between the clamp and the vamp, a pair of feed rolls arranged to engage opposite sides of the untrimmed portion of the vamp projecting beyond the clamp, said feed rolls being located adjacent to said gage, means positioned adjacent to said gage for trimming the vamp along a line parallel to and adjacent to the top margin of the clamp, and a pair of driven rolls arranged to engage opposite sides of the trimmed surplus portion of the vamp for applying tension thereto, said last-mentioned rolls being conical with the large diameter of the rolls spaced above the line of trimming.

7. In a machine for trimming the upper margin of the vamp of a moccasin, a pair of feed rolls arranged to engage opposite sides of the upper margin of the vamp, trimming means adjacent to said feed rolls for trimming the margin of the vamp after the work has passed between said feed rolls, a pair of driven rolls arranged to engage opposite sides of the surplus portion of the vamp after it has been trimmed, and means for imparting to the work-engaging portions of said second pair of rolls a peripheral speed greater than that of the feed rolls.

8. In a machine for trimming the upper margin of the vamp of a moccasin, a pair of feed rolls arranged to engage opposite sides of the upper margin of the vamp, means for trimming the margin of the vamp being fed by said rolls, a pair of driven conical rolls arranged to engage opposite sides of the surplus trimmed margin of the vamp, the smaller ends of the conical rolls being in line with the feed rolls, and means for imparting to said conical rolls a peripheral speed sufficient to exert a tension upon the trimmed portion of the margin.

9. In a machine for trimming the upper margin of the vamp of a moccasin, a pair of feed rolls arranged to engage opposite sides of the upper margin of the vamp, trimming means adjacent to said feed rolls for trimming the margin of the vamp after the work has passed between said feed rolls, a pair of driven rolls arranged to engage opposite sides of the surplus margin of the vamp after it has been trimmed, means for imparting to said second pair of rolls a peripheral speed greater than that of the feed rolls, and means for separating said second pair of rolls sufficiently to render them inoperative.

10. In a machine for trimming the vamp of a moccasin, feeding means arranged to engage the upper margin of the vamp, means for trimming the margin beyond the point of engagement of the feeding means with the vamp, means for applying a tension to the surplus trimmed por-

tion of the vamp, said tensioning means comprising a pair of driven rolls engaging opposite sides of the trimmed portion and rotating at a sufficiently high speed to impart a tension to the trimmed portion of the vamp, said rolls being shaped to exert a heightwise pull on the trimmed margin relative to the sides of the vamp.

11. In a machine for trimming the vamp of a moccasin secured to a last by a clamp surrounding the vamp, a conical feed roll arranged to engage the portion of the vamp extending beyond the upper margin of the clamp, a gage adjacent to the periphery of said feed roll against which the upper margin of the clamp may be held to guide the work, said guide including a portion arranged to extend between the clamp and the vamp, a second feed roll arranged to hold the margin of the vamp against the first feed roll and movable toward and away therefrom, a knife mounted for reciprocation in shearing relation to the back of said first feed roll and arranged to engage the margin of the vamp adjacent to the guide for trimming the vamp along a line close to the upper margin of the clamp, a second pair of feed rolls arranged to engage the trimmed surplus portion of the vamp, and means for driving said second pair of feed rolls fast enough to exert a tension on the margin of the vamp as it is being trimmed.

12. In a machine of the class described, a cutter, means for feeding a work piece past said cutter to be trimmed thereby, a pair of rolls for engaging opposite sides of the trimmed surplus portion of the work, rotatable shafts supporting said rolls, a drive shaft, a worm carried by said drive shaft, worm gears carried by said roll-supporting shafts engaging said worm at opposite sides thereof, and means for pivoting one of said roll-supporting shafts about the axis of said drive shaft to vary the relative positions of said rolls.

13. In a machine of the class described, a conical feed roll rotatable about a substantially vertical axis, a cutter operably associated therewith for trimming a work piece as it is fed by said feed roll, a second feed roll cooperating with said first feed roll to feed the work, a pair of auxiliary feed rolls arranged to engage the trimmed surplus portion of the work in a plane passing substantially through the work-engaging portion of said first feed roll, means for moving said second feed roll away from said first feed roll, and means for varying the distance between said auxiliary feed rolls to render them effective or ineffective to feed the trimmed surplus portion of the work.

14. In a machine of the class described, a conical feed roll rotatable about a substantially vertical axis, a cutter operably associated therewith for trimming a work piece as it is fed by said feed roll, a second feed roll cooperating with said first feed roll to feed the work, a pair of auxiliary feed rolls arranged to engage the trimmed surplus portion of the work in a plane passing substantially through the work-engaging portion of said first feed roll, said auxiliary feed rolls having roughened conical work-engaging surfaces arranged to exert a heightwise pull on the trimmed surplus portion of the work, means for moving said second feed roll away from said first feed roll, and means for varying the distance between said auxiliary feed rolls to render them effective or ineffective to feed the trimmed surplus portion of the work.

15. In a trimming machine, a feed roll mounted for rotation about a substantially vertical axis, a second feed roll arranged to hold a work piece against said first feed roll, a cutter for trimming a work piece as it is fed between said feed rolls, an upwardly extending shaft supporting said second feed roll, a worm gear at the upper end of said shaft, a drive shaft at right angles to said upwardly extending shaft and extending generally in the direction of feed, a worm on said drive shaft engaging said worm gear, and means for mounting said upwardly extending shaft for pivotal movement about the axis of said drive shaft.

16. In a trimming machine, a conical feed roll mounted for rotation about a substantially vertical axis, a second feed roll arranged to hold a work piece against said first feed roll, a cutter for trimming a work piece as it is fed between said feed rolls, an upwardly extending shaft supporting said second feed roll, a worm gear at the upper end of said shaft, a drive shaft at right angles to said upwardly extending shaft, a worm on said drive shaft engaging said worm gear, and means for mounting said upwardly extending shaft for pivotal movement about the axis of said drive shaft.

17. In a trimming machine, a conical feed roll mounted for rotation about a substantially vertical axis, a second feed roll arranged to hold a work piece against said first feed roll, a cutter for trimming a work piece as it is fed between said feed rolls, an upwardly extending shaft supporting said second feed roll, a worm gear at the upper end of said shaft, a drive shaft at right angles to said upwardly extending shaft, a worm on said drive shaft engaging said worm gear, and means for mounting said upwardly extending shaft for pivotal movement about the axis of said drive shaft.

18. In a trimming machine, a conical feed roll mounted for rotation about a substantially vertical axis, a second feed roll arranged to hold a work piece against said first feed roll, a cutter for trimming a work piece as it is fed between said feed rolls, an upwardly extending shaft supporting said second feed roll, a worm gear at the upper end of said shaft, a drive shaft at right angles to said upwardly extending shaft, a worm on said drive shaft engaging said worm gear, and means for mounting said upwardly extending shaft for pivotal movement about the axis of said drive shaft.

19. In a trimming machine, a conical feed roll mounted for rotation about a substantially vertical axis, a second feed roll arranged to hold a work piece against said first feed roll, a cutter for trimming a work piece as it is fed between said feed rolls, an upwardly extending shaft supporting said second feed roll, a worm gear at the upper end of said shaft, a drive shaft at right angles to said upwardly extending shaft, a worm on said drive shaft engaging said worm gear, and means for mounting said upwardly extending shaft for pivotal movement about the axis of said drive shaft.

20. The method of trimming the vamp of a moccasin secured to a last by a clamp surrounding the vamp which comprises cutting the surplus material from the top margin of the vamp along a line parallel to the upper edge of the clamp and exerting a pull on the trimmed surplus portion of the vamp to smooth out wrinkles as the material is being cut.

21. The method of trimming the vamp of a moccasin secured to a last by a clamp surrounding the vamp which comprises guiding the work by the upper edge of the clamp past a trimming knife and simultaneously exerting a pull on the trimmed surplus portion of the vamp to smooth out wrinkles.

22. The method of trimming the vamp of a moccasin secured to a last by a clamp surrounding the vamp which comprises feeding the work past a trimming knife and maintaining the vamp at a predetermined heightwise and angular position relative to the knife by the engagement of the clamp with a guide.

23. The method of trimming the vamp of a moccasin secured to a last by a clamp surrounding the vamp which comprises feeding the work past a trimming knife and maintaining the vamp at a predetermined heightwise and angular position relative to the knife by the engagement of the clamp with a guide, and during the feeding

movement, exerting a strong pull on the trimmed surplus portion of the vamp to smooth out wrinkles as the material is being cut.

22. The method of trimming the vamp of a moccasin secured to a last by a clamp surrounding the vamp which comprises feeding the work past a trimming knife and maintaining the vamp at a predetermined heightwise and angular posi-

tion relative to the knife by the engagement of the clamp with a guide, and during the feeding movement exerting on the trimmed surplus portion of the vamp a strong lengthwise pull having a heightwise component relative to the sides of the vamp.

FRED ASHWORTH.
